UNITED STATES PATENT OFFICE.

JESSE D. PADGITT, OF DALLAS, TEXAS.

COLLAR.

1,209,196.

Specification of Letters Patent. Patented Dec. 19, 1916.

Application filed July 27, 1916. Serial No. 111,666.

To all whom it may concern:

Be it known that I, JESSE D. PADGITT, a citizen of the United States, residing at Dallas, in the county of Dallas and State of Texas, have invented a new and useful Collar, of which the following is a specification.

The device forming the subject matter of this application is a horse collar, and the invention aims to provide novel means where-
10 by the fore-wale of the collar will be caused to grip the hames.

With the above and other objects in view which will appear as the description pro-
ceeds, the invention resides in the combina-
15 tion and arrangement of parts and in the details of construction hereinafter described and claimed, it being understood that changes in the precise embodiment of the in-
vention herein disclosed can be made within
20 the scope of what is claimed, without de-
parting from the spirit of the invention.

In the drawings, Figure 1 shows in side elevation, a hame collar constructed in ac-
cordance with the present invention; Fig. 2
25 is a fragmental cross-section showing one side of the hame collar delineated in Fig.
1; and Fig. 3 is a sectional detail illustrating the manner in which the wale is made to grip the hames. Fig. 4 is a sectional detail
30 showing a slight modification in the invention.

In the drawings there is shown a collar comprising a body 1 and a bendable angular fore-wale 2. The body 1 comprises walls 3 and 4 which may be united by a seam 5. Disposed within the body 1 is a packing 11 which may be made of any material. The wall 3 of the body 1 is prolonged to form the inner wall 7 of the fore-wale 2, and the wall
40 4 of the body is prolonged to form the outer wall 6 of the fore-wale 2. Disposed between the walls 6 and 7 of the fore-wale 2 is an angular reinforcement 8 which may be made out of relatively stiff leather or any
45 other material. The walls 7 and 6 of the fore-wale 2 are united with the reinforce-
ment 8 by means of stitchings 9. The inner wall 7 is shorter than the outer wall 6, measured transversely of the collar, and, as
50 shown at 10, a portion of the inner wall 7

bridges the inner angle 14 of the fore-wale. When the hames 11 are placed in the fore-wales 2 and are tightened down, the hames bear against the portions 10 of the inner walls of the fore-wales and cause the fore-wales to swing inwardly and grip the hames
55 as shown in Fig. 3.

The fore-wale need not be formed in-
tegrally with the body, as above described.

In Fig. 4 of the drawings, parts hereto-
fore described have been designated by the numerals previously used, with the suf-
fix "a".

As indicated at 50, the fore-wale, which is detachable, has been shown connected with the body portion of the collar. Fig. 4 merely illustrates one of the many ways whereby the fore-wale may be detachably united with the body of the collar, and a collar-maker will be entirely competent to con-
70 nect the fore-wale with the body of the collar in any way which is considered expedi-
ent or desirable, either according to the showing of Fig. 4 or otherwise.

Having thus described the invention, what is claimed is:-

1. A bendable angular horse-collar fore-wale including a strip connecting trans-
versely remote portions of the fore-wale and bridging the inner angle of the fore-wale, 80 the strip being constructed and arranged to be depressed into the angle of the fore-wale by a hame, to bend the fore-wale into hame-
gripping position.

2. A bendable angular horse-collar fore-wale including inner and outer walls and a reinforcement between the walls, the reinforce-
ment forming an inner angle in the wale, and the inner wall being connected with the reinforcement at transversely re-
mote points and bridging the inner angle, 90 the inner wall being constructed and ar-
ranged to be depressed into the inner angle of the fore-wale by a hame to bend the fore-
wale into hame-gripping position.
95

In testimony that I claim the foregoing as my own, I have hereto affixed my signature.

JESSE D. PADGITT.
